UNITED STATES PATENT OFFICE.

ADOLPH P. VANDREY, OF MANKATO, MINNESOTA.

DOOR HOLDER.

Application filed May 12, 1925. Serial No. 29,748.

To all whom it may concern:

Be it known that I, ADOLPH P. VANDREY, a citizen of the United States, residing at Mankato, in the county of Blue Earth, State 5 of Minnesota, have invented certain new and useful Improvements in Door Holders; and I do hereby declare the following to be a full, clear, and exact description of the invention, such as will enable others skilled in 10 the art to which it appertains to make and use the same.

This invention relates to new and useful improvements in holding devices, and particularly to devices for holding doors in open 15 position.

One object of the invention is to provide a door holder which is simple in construction, cheap to manufacture, and effective in use.

20 Another object is to provide a device of this character which is automatic in its operation to engage and hold a door in open position, and which is readily actuated, manually, to be released from the door.

25 Another object is to provide a novel and simple means for releasing the door engaging detent, whereby the number of parts is limited to a minimum.

Other objects and advantages will be apparent from the following description when 30 taken in connection with the accompanying drawing.

In the drawing:

Figure 1 is a perspective view of the door holding device in operation.

Figure 2 is a vertical longitudinal central sectional view through the device.

Referring particularly to the accompanying drawing, 10 represents a fragment of the 40 upper portion of a door, and 11 a portion of a wall, in connection with which the present invention is particularly adapted for use.

An angular U-shaped member 12 is provided with the opposite laterally turned feet 45 13, on the legs thereof, and said legs are secured to the face of the wall 11 by means of the screws 14. The U-shaped portion of this member 12 extends at right angles from the face of the wall, and at a sufficient height to 50 permit the upper edge of the door 10 to eas-

ily pass thereunder, when said door is in open position and adjacent said wall. Disposed transversely through the legs of the member 12, adjacent the bight of said member is a pivot pin 15, and pivotally supported 55 on this pin, and extending inwardly in the direction of the wall 11, is an angular U-shaped member 16, the bight portion of which is provided with a central opening 17. This member 16 is adapted to swing downwardly, below the lower edges of the legs of the member 12, to a sufficient distance to be engaged and raised by the upper edge of the door, when said door is moved under the member 12, said member 16 then swinging 60 downwardly to engage with the outer face of the upper portion of the door, as clearly seen in Figure 1, of the drawing.

Extending transversely through the inner portions of the legs of the member 12, is 70 a pivot pin 18, and mounted on this pin, for rocking movement, is a member 19, the end adjacent the member 16 being reduced and disposed in an opening 20, formed in the bight portion of the said member 16. To 75 the other end of the pivoted member 19 there is secured the upper end of a cord or wire 21, said wire depending in close proximity to the wall 11, within convenient reach to be pulled for the purpose of rocking the member 19, to transmit such movement to the member 16, whereby to raise the latter member above the edge of the door, and permit the door to be swung into closed position.

80 What is claimed is:

1. A door holder comprising a bracket having attaching feet, a yoke pivotally mounted in the bracket and normally gravitating below the bracket for engagement by a door, the yoke having an opening, a rockable member pivotally supported by the bracket and having a reduced end engaged operatively in the opening of said pivoted yoke, and operating means carried by the other end of the rockable member whereby to move the yoke out of engagement with a door.

2. A door holder comprising a yoke-shaped bracket having laterally extending attaching feet, a yoke pivotally mounted in

the bracket adjacent the bight thereof and normally gravitating below the bracket for engagement by a door, the bight of the pivoted yoke having an opening, a rockable member pivotally supported by the arms of the bracket inwardly of the pivoted yoke and having a reduced end engaged opera-

tively in the opening of said member, and operating means carried by the other end of the rockable member whereby to move the 10 yoke out of engagement with a door.

In testimony whereof, I affix my signature,

ADOLPH P. VANDREY.
